UNITED STATES PATENT OFFICE

110,997

DESIGN FOR A RING

Morris Goodman, Indianapolis, Ind.

Application June 27, 1938, Serial No. 78,083

Term of patent 7 years

To all whom it may concern:

Be it known that Morris Goodman, a citizen of the United States, residing at Indianapolis, in the county of Marion and State of Indiana, has invented a new, original, and ornamental Design for a Ring, of which the following is a specification, reference being had to the accompanying drawing, forming a part thereof.

Fig. 1 is a side elevation of a ring embodying the invention;

Fig. 2, an end elevation; and

Fig. 3, a top plan view.

I claim:

The ornamental design for a ring, as shown.

MORRIS GOODMAN.
